United States Patent Office

Des. 205,140
Patented June 28, 1966

205,140

COMBINED TELEPHONE HANDSET DESK STAND AND COMPARTMENTED TRAY OR SIMILAR ARTICLE

Henry Dreyfuss, South Pasadena, Calif., Harry W. McCune, Indianapolis, Ind., and Cornelius Tanis, Colts Neck, N.J., assignors to Bell Telephone Laboratories, Incorporated, New York, N.Y., a corporation of New York

Filed Apr. 19, 1965, Ser. No. 84,859

Term of patent 14 years

(Cl. D26—14)

FIG. 2

FIG. 1 is a perspective view of a combined telephone handset desk stand and compartmented tray or similar article, showing our new design; and

FIG. 2 is a right side elevational view, the opposite side being substantially a mirror image thereof; the back of the combined telephone handset desk stand and compartmented tray is a substantially flat, unornamented surface.

We claim:

The ornamental design for a combined telephone handset desk stand and compartmented tray or similar article, substantially as shown and described.
